United States Patent Office.

JOHN W. CURRIER, OF SPRINGFIELD, MASSACHUSETTS.

Letters Patent No. 90,731, dated June 1, 1869.

IMPROVED DEVICE FOR HOLDING INTERFERING-BANDS IN PLACE.

The Schedule referred to in these Letters Patent and making part of the same.

To all whom it may concern:

Be it known that I, JOHN W. CURRIER, of Springfield, Hampden county, State of Massachusetts, have invented a new and useful Device to Prevent the Interfering-Bands Applied to the Hoofs of Horses from Slipping up Around the Ankle; and I do hereby declare that the following is a full and clear description thereof, reference being had to the accompanying drawings, and to the letters of reference marked thereon.

In the drawings—

Figure I shows a front view;

Figure II, a side view of my device in use; and

Figure III is a detail view of the device in perspective;

Figure IV showing a different construction of the same device.

This device is meant to be applied to those rubber or leather interfering-bands which are sprung or fastened around the hoofs of the interfering horse.

Usually there is great difficulty in arranging these bands, so that they will not slip up upon the ankle, and when there is any snow on the ground, it is impossible to fasten them down without using an auxiliary device.

My device consists of a wire double-hook, B, which

fits under the toe of the shoe of the horse, and grasps the band A in front, as shown in Figs. I and II.

The toe-calk fits in between the wires, and prevents the hook from slipping off either side.

The construction of this hook is shown in detail in Fig. III.

Sometimes, however, I form it of a metal plate, which is bent around in the same form, but has a hole cut into it at C, to allow the calk to pass through. This is shown in detail in Fig. IV.

By this means I completely prevent the band A from slipping up, and render it useful where at best it was only partially successful, and required constant adjustment.

Now, having described my invention,

What I claim as new, and desire to secure by Letters Patent, is—

In combination with the rubber band A, the wire or metal hook B, constructed as herein described, and for the purpose set forth.

J. W. CURRIER.
